US0D1035040S

(12) **United States Design Patent** (10) Patent No.: **US D1,035,040 S**
 Saiz et al. (45) Date of Patent: ** Jul. 9, 2024

(54) **FIXED APPARATUS AND EQUIPMENT FOR LABORATORIES**

(71) Applicant: **NETZSCH-Gerätebau GmbH**, Selb (DE)

(72) Inventors: **Oliver Saiz**, Nuremberg (DE); **Mareike Roth**, Nuremberg (DE)

(73) Assignee: **NETZSCH-Gerätebau GmbH**, Selb (DE)

(**) Term: **15 Years**

(21) Appl. No.: **29/867,118**

(22) Filed: **Oct. 11, 2022**

(30) **Foreign Application Priority Data**

Apr. 11, 2022 (EM) 008934947

(51) **LOC (14) Cl.** **24-01**

(52) **U.S. Cl.**

USPC **D24/232**

(58) **Field of Classification Search**

(57) **CLAIM**

The ornamental design for a fixed apparatus and equipment for laboratories, as shown and described.

DESCRIPTION

FIG. 1 is a front isometric view of a fixed apparatus and equipment for laboratories in accordance with the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the fixed apparatus and equipment that form no part of the claimed design.

1 Claim, 7 Drawing Sheets
